J. A. HUTH,
AUTOMOBILE HOOD CLAMP.
APPLICATION FILED NOV. 1, 1920.

1,425,773.

Patented Aug. 15, 1922.

INVENTOR:

John A. Huth

BY *Allen Belcher*

ATTORNEYS.

UNITED STATES PATENT OFFICE.

JOHN A. HUTH, OF CINCINNATI, OHIO, ASSIGNEE TO STANLEY M. LAWSON, OF CINCINNATI, OHIO.

AUTOMOBILE HOOD CLAMP.

1,425,773.

Specification of Letters Patent. Patented Aug. 15, 1922.

Application filed November 1, 1920. Serial No. 421,002.

To all whom it may concern:

Be it known that JOHN A. HUTH, a citizen of the United States, and a resident of the city of Cincinnati, in the county of 5 Hamilton and State of Ohio, has invented certain new and useful Improvements in Automobile Hood Clamps, of which the following is a full, clear, and exact description, reference being had to the drawings 10 forming part of this specification.

My invention relates to clamps for automobile hoods, which are normally secured along the sides of the frame in motor vehicles and engage the sides of the engine hood, 15 to hold it down tightly in place.

Devices of the above character are common in the art, but according to my information are not of a structure which it is easy and inexpensive to manufacture and 20 comprise an over number of parts which must be assembled and secured together at considerable labor cost.

It is the object of my invention to provide a clamp structure which may be struck up out of sheet metal and comprises but few 25 parts of easy assemblage, and is strong and durable.

In one of the forms of my invention, in fact, the entire body of the clamp exclusive 30 of the mounting thereof and the spring rod is formed of a single piece of metal, formed up and secured with a single rivet, same providing for both body, finger hold and engaging hook.

I accomplish my objects and various other 35 advantages to be noted by that certain construction and arrangement of parts to be hereinafter more specifically pointed out and claimed.

40 In the drawings,

Figure 1 is an elevation of the clamp.

Figure 2 is a perspective view of the stamped out piece from which I form the body of my clamp.

45 Figure 3 is an elevation of the spring rod.

Figure 4 is a perspective view of the hinge pin.

Figure 5 is a plan view of the mounting piece, before it is formed up.

50 Figure 6 is a perspective view of the completed mounting piece.

Figure 7 is an elevation of a modified form of my invention.

The body piece of the preferred form of 55 my invention is made of a stamped out strip

of metal, having two semi-tubular arms 1 and 2, a flat central piece 3 and curved finger hold portion 4 and a shorter curved hook portion 5.

When this piece is formed up into the 60 complete body of the clamp, the two tubular pieces are bent so as to coincide with each other, and form a hollow cylindrical body, with the adjacent portions of the hook and finger hold members at the end of said body 65 riveted together as at 6. The finger hold portion and the hook portion are then bent outwardly, as shown in Figure 2, whereupon the body is complete without any additions.

During the process of forming the body. 70 as above outlined, a rod 7 is set into the hole 8 in the flat portion or central piece 3, so as to be confined within the completed body, this rod having a head 8^a and a spring 9 set around it. Thus when the body is 75 formed, the rod will be spring impelled inwardly of the body, and can be used for purposes of mounting the clamp body and giving it the desired spring action in holding down an engine hood. 80

The mounting piece or hinge piece of the clamp body may be formed of a metal piece stamped out to have a body 10 and ears 11, 11 which when bent around as at 12, 12, will form mounting clips for a hinge 85 pin 13. This hinge pin is inserted through the said clips or eyes, and through an eye 14 in the rod 7, and suitably upset, to form a permanent hinged connection.

The entire device is then complete and 90 ready for mounting along the side of a vehicle frame, for use as a hood clamp.

The method of mounting the rod is not essential to my invention, as various models of motor vehicles have different methods of 95 mounting the clamp rods. The method shown is merely a simple one of easy manufacture and sturdy character.

In instances where the clamp must engage a hood that is located nearer the edge 100 of the engine hood than will be accommodated by the clamp now described, I form up my body portion in the same way, but rivet on the finger hold and the hook portion.

Thus in the instance shown in Figure 7 105 the body portion is made of a single piece struck up and formed as previously described, with the omission of the finger and hook portions.

The finger piece 15 having two wings, in 110

this case, is mounted on the upper end of the clamp by the rivet 16 that, as in the former case, holds the body together. The hook piece 17 is mounted on one side of the body near the base thereof by means of a suitable rivet 18, prior to the forming up of the complete device.

It is not desired because of my failure to note other modifications of my invention 10 above to exclude from the scope of the claims that follow those obvious mechanical equivalents which will occur to those skilled in the art, as substitutes for the parts described.

15 Having thus described my invention, what I claim as new and desire to secure by Letters Patent, is:—

1. A hood clamp for motor vehicles and the like which has a body portion formed 20 of a single strip of metal bent into a half round shape, with a flat central portion and flat end portions, said strip being bent together to bring the edges of the half round together to form a tubular body and secured 25 in permanent form by the lapping flat ends.

2. A hood clamp for motor vehicles and the like which comprises a body portion formed of a single strip of metal having 30 matching halves adapted to be brought together to form a body, a central portion adapted to form a connecting web between the halves, and a base of the body, and ends adapted to be lapped upon bringing together the halves, and means for securing 35 said lapped ends together.

3. A hood clamp for motor vehicles and the like which comprises a body portion formed of a single strip of metal having 40 matching halves adapted to be brought together to form a body, a central portion adapted to form a connecting web between

the halves, and a base of the body, and ends adapted to be lapped upon bringing together the halves, and means for securing said lapped ends together, said ends comprising further an extension away from one of the lapped portions forming a finger hold. 45

4. A hood clamp for motor vehicles and the like, which comprises a hollow body, a 50 hook, and a finger hold separate from the hook formed from a single piece of metal bent on itself and secured together.

5. A hood clamp for motor vehicles and the like, which comprises a hollow body, a 55 hook, and a finger hold separate from the hook formed from a single piece of metal bent on itself and secured together, said body having a hole in the base of said body for the journaling of a spring pin. 60

6. A hood clamp for motor vehicles and the like, which comprises a hollow body, a hook, and a finger hold separate from the hook formed from a single piece of metal bent on itself and secured together, said 65 body having a hole in the base of said body for the journaling of a spring pin, a spring pin in said body and extending from said hole, said pin having a hole in its lower end, and a hinge pin in said hole for purpose of 70 securing to the motor car frame.

7. A hood clamp for motor vehicles and the like, which comprises a pin having a 75 spring thereon, and a metal strip provided with a hole for the pin and bent up around the pin to house it in an enclosed body, said strip being so secured together around the pin, whereby the spring and pin may be mounted in the holder during the formation thereof.

JOHN A. HUTH.
